Primary Examiner — Alison M Ofstun

(74) *Attorney, Agent, or Firm* — Dilworth & Barrese, LLP

(57) **CLAIM**

The ornamental design for a facial hair grooming guide, as shown and described.

DESCRIPTION

FIG. 1 is a perspective view of the facial hair grooming guide showing my new design;

FIG. 2 is a front view of the facial hair grooming guide showing my new design;

FIG. 3 is a back view of the facial hair grooming guide showing my new design;

FIG. 4 is a left side view of the facial hair grooming guide showing my new design;

FIG. 5 is a right side view of the facial hair grooming guide showing my new design;

FIG. 6 is a top view of the facial hair grooming guide showing my new design;

FIG. 7 is a bottom view of the facial hair grooming guide showing my new design;

FIG. 8 is a front view of the facial hair grooming guide, shown in an environment of use; and,

FIG. 9 is another front view of the facial hair grooming guide, shown in an environment of use.

In the drawings, the broken lines illustrate environmental subject matter only and form no part of the claimed design.

1 Claim, 7 Drawing Sheets
